UNITED STATES PATENT OFFICE.

CHARLES F. BAUER, OF MCCONNELSVILLE, OHIO, ASSIGNOR OF ONE-HALF
TO GEORGE H. BAIN, OF MCCONNELSVILLE, OHIO.

PIPE-TONGS.

SPECIFICATION forming part of Letters Patent No. 700,008, dated May 13, 1902.

Application filed April 20, 1901. Serial No. 56,711. (No model.)

To all whom it may concern:

Be it known that I, CHARLES F. BAUER, a citizen of the United States, and a resident of McConnelsville, in the county of Morgan and State of Ohio, have made a certain new and useful Invention in Pipe-Tongs; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a side elevation of my tongs, partly in section, and showing the jaws open. Fig. 2 is a side elevation of the same from the opposite side, showing the jaws closed. Fig. 3 is an edge elevation of my tongs. Fig. 4 is a similar view from the opposite side. Fig. 5 is a top plan view of the tongs.

The invention relates to gripping devices such as are made for pipe-tongs and nippers; and it consists in the novel construction and combinations of parts, as hereinafter set forth.

In the accompanying drawings, illustrating the invention, the letter *a* designates the main or fixed jaw-bar, having its jaw *b* on the same side as its handle or portion *c*. This jaw-bar is slotted at *d* to receive the pivotal fulcrum-lug *e* of the short handle bar or lever *f*, which is connected to the bar *a* by the pivot-pin *g* in said slot. At the slotted portion the back of the bar *a* is usually provided with a cutter-bearing *h*, which serves to strengthen the bar in this part. This cutter-bearing extends to the slot *d*, its inner face being flush with the wall of said slot.

The letter *k* indicates a short jaw-lever which is pivoted to the bar *a* by the pivot-pin *l* in said slot at a point nearer the jaws than the pivot-pin *g*, which connects the handle-bar *f* to the main jaw-lever. The jaw-lever *k* is provided with a curved jaw *m*, which is formed with a pivotal part or tang *t*, which extends through the slot *d* of the main jaw-bar, such slot being made long enough to accommodate both said tang and the lug *e*. The tang is connected to the lug *e* by means of lateral-position links *n* and is usually extended

and given proper angular relation to the jaw *m* for service as a cutter in connection with the cutter-bearing *h* of the main bar *a*.

When the jaws are closed, by pressing the handle-bars toward each other the cutter is closed alongside the bearing. By working the short lever-handle *f* the cutter is operated, the location of the cutter-bearing remaining fixed and steady on the main bar. The grip-jaws *b* and *m* are suitably serrated on their concave inner surfaces to adapt them for gripping pipe and articles of like nature. These jaws may also be provided with serrated grooves extending inward from their ends to serve as a grip for turning nipples and articles of similar presentation.

In connecting the tang of the short jaw-lever to its handle-lever it is designed to provide this short handle with a powerful leverage, and to that end the back of the lug *e* of this short lever *f* is provided with the pivot-bearing *p* for the pin *q*, connecting the links *n* near to and a little in advance of the pivot *g*. The links *n* extend through the slot *d* and are connected to the tang of the jaw-lever *k* by the pin *s*. The links are well protected between the slot-walls and the sides of the lever tang and lug *e* and may be made of comparatively thin metal, as tensile strength only is required.

This instrument is designed to facilitate work upon pipes in corners and near walls where it would be difficult to operate with tongs of the usual cross-lever style. Owing to the angular movement in operating these tongs being altogether on the side opposite the main jaw-bar, which remains steady and true, there is no tendency of its jaw *b* to push against the wall or other obstruction and no action of its handle portion *c* to press against such wall or obstruction, such pressure being liable not only to throw the jaw out of action, but also to prevent the proper working grasp of the instrument.

The main jaw-bar is curved or bent inward in a somewhat angular manner from its jaw end and from its handle portion to its slotted part in order to give the handle action proper balance and to provide a proper presentation for the jaws.

Having described this invention, what I claim, and desire to secure by Letters Patent, is—

The wrench herein described, consisting of the integral jaw and handle-bar having a single slot, the coöperating short jaw and its handle-lever separately formed and pivoted in said slot, and the thin link-plates extending through the said slot and connecting the short

jaw and its handle-lever, substantially as specified.

In testimony whereof I affix my signature in presence of two witnesses.

CHARLES F. BAUER.
